UNITED STATES PATENT OFFICE.

HERMAN F. BUSCH, OF MILLVALE, PENNSYLVANIA, ASSIGNOR TO ARMSTRONG CORK COMPANY, OF PITTSBURGH, PENNSYLVANIA, A CORPORATION OF PENNSYLVANIA.

METHOD OF MAKING INSOLES FOR SHOES.

1,279,980.

Specification of Letters Patent. Patented Sept. 24, 1918.

Application filed August 7, 1917. Serial No. 184,936.

To all whom it may concern:

Be it known that I, HERMAN F. BUSCH, a citizen of the United States, residing at Millvale, in the county of Allegheny and State 5 of Pennsylvania, have invented a new and useful Improvement in Methods of Making Insoles for Shoes, of which the following is a full, clear, and exact description, reference being had to the accompanying drawings, forming part of this specification, in which—

Figure 1 is a plan view and Fig. 2 is a cross section of a finished insole made in accordance with my invention; and

15 Figs. 3 and 4 are cross sectional views showing different stages of the operation.

My invention has relation to the method of making that class of insoles which are used in the manufacture of welt shoes, and 20 which are provided with a stitching rib on the under surfaces to which the welt and upper are secured.

Various methods have heretofore been devised for providing an insole with a stitching rib of this character, the rib in some cases being formed up from the material of the body of the insole, and in other cases comprising a separate strip, cord, tape or the like, secured to the insole and incased in 30 a covering of canvas or other fabric. In insoles of the last named type, the tape, cord or other material has been secured to the insole by stitching, the stitches extending through the cord or tape. This has been 35 found objectionable owing to the fact that in securing the upper and welt to the insole, the stitching of these parts frequently breaks a considerable number of the stitches which secure the rib to the insole. In so far 40 as the strength of the shoe is largely dependent upon the security of the fastening of this rib, this is, of course, detrimental.

The object of my invention is to provide 45 a method of making an insole having a stitching rib applied thereto and which is free from any stitches extending through it, being secured to the insole by stitches which secure the fabric covering to the insole.

50 Referring to the accompanying drawings in which I have illustrated the embodiment of my invention, the numeral 2 designates the body of the insole, 3 the cord, tape or other rib-forming member, and 4 the bottom 55 covering of canvas, the latter incasing the

cord or tape 3, and covering the entire lower surface of the insole. This covering is secured to the insole by a double line of stitching running around each side of the rib closely adjacent to the base thereof. 60

In manufacturing my improved insole, I first provide a shaped insole body or blank, then apply the tape or cord thereto without securing means, and then apply the fabric covering 4, the latter having a coating of adhesive material on its inner surface. The covering fabric is then shaped over the cord or tape, after which it is stitched to the insole body. The manner of carrying out 65 these several steps may be varied in detail. 70

In the particular method illustrated in the accompanying drawings, I provide a block or form 5, which is similar in outline to the contour of the insole, but is of smaller dimensions, so that when applied to the bottom surface of the insole it will just occupy 75 the space within the stitching rib. The

fabric covering is then placed underneath this block with its edge portions upstanding, or partially upstanding, as shown in Fig. 3. 80 The cord or tape 3 is then placed underneath the edge portions of the fabric, against and around the former block, as also shown in Fig. 3. This tape may be fed from any suitable holder through a suitable guide 6. 85

7 designates a presser roller which follows the tape or cord and presses the edge portions of the fabric down into contact with the surface of the insole, and also in coaction with the block properly shapes the 90 canvas over the tape, or cord, as shown in Fig. 4. The insole can then be removed and is ready for sewing on the double needle machine of well known type. The two lines of stitches 8 not only firmly secure the fabric 95 covering to the insole, but also, of course, hold the cord or tape securely in place without any stitches, however, penetrating the cord or tape. 100

The fabric covering may either be previously cut to shape or it may be trimmed coincidentally with its final application to the sole or coincidentally with the stitching by any suitable trimming means, such means being well known in the art. 105

My invention provides an improved method of making an insole which is free from the objections previously noted, which can be readily manufactured, and which gives a strong and serviceable stitching rib. 110

I claim:

1. The herein described method of making insoles, which consists in providing a shaped blank, then placing a covering on the blank, then laying a stitching rib forming member between the covering and the blank along the edge of the blank and shaping the covering around the stitching rib forming member, and then stitching said covering to the body at each side of the rib, substantially as described.
2. The herein described method of making insoles, which consists in providing a shaped blank, then placing a covering and a former on said blank, then laying a stitching rib forming member between the cover and the blank along the edge of the former and ad-

jacent to the edge of the blank, and then stitching said covering to the body at each side of the rib, substantially as described.

3. The herein described method of making insoles, which consists in providing a shaped blank, then placing a covering and a former on said blank, then laying a stitching rib forming member between the cover and the blank along the edge of the former and adjacent to the edge of the blank, then shaping the covering around the rib forming member, and then stitching said covering to the body at each side of the rib, substantially as described.

In testimony whereof, I have hereunto set my hand.

HERMAN F. BUSCH.
